UNITED STATES PATENT OFFICE

2,583,388

CONDUCTING SEAL FOR HIGH-PRESSURE
LAMPS

Evan Herbert Nelson, Harrow Weald, and Ernest Benjamin Power, Kenton, England, assignors to General Electric Company, a corporation of New York

Application September 14, 1948, Serial No. 49,144
In Great Britain May 1, 1947

1 Claim. (Cl. 49—92.5)

1 This invention relates to conductor-seal bodies of the type comprising a metal rod conductor passing along the axis of a tube of vitreous material, which tube fits closely around, but is not sealed to, the rod over part of the length of the tube, and at one end is expanded in diameter and sealed to a button of glass, which button is itself sealed around the rod to form a vacuum-tight seal.

The term "button" does not imply any particular shape for the body of glass constituting the button, but in general it is found desirable that the button should consist of a short sleeve sealed around the rod and a flange extending from the sleeve for an appreciable distance approximately at right angles to the axis of the rod.

Conductor-seal bodies of the type specified are often used for sealing a conductor through the vitreous envelope of an electric discharge device, the tube of vitreous material containing the conductor being sealed to the sides of a hole in the envelope through which the conductor passes. In some cases the envelope is of hard vitreous material to withstand heat developed during operation of the device, and it is then desirable that the tube of the conductor-seal body should be of similar hard vitreous material and should be sealed to the metal rod conductor through a button of intermediate glass.

By hard vitreous material is meant, for the purpose of this specification, a vitreous material whose thermal expansion coefficient is so much less than that of the metal of the rod that it cannot be sealed directly to the rod without considerable risk of cracking of the seal on heating. The vitreous material and rod metal particularly contemplated for use with this invention are quartz and tungsten, respectively.

By "intermediate glass" is meant glass whose thermal expansion coefficient lies between that of the hard vitreous material and the metal of the rod and which can be sealed to both without much risk of cracking of the seals on heating. The intermediate glass may consist of several sections of glasses of different thermal expansion coefficients, graded from the highest nearest to the rod to the lowest nearest to the hard vitreous material. Such graded seals are well known and species thereof are disclosed in U. S. Patent No. 2,177,685, issued October 31, 1939 to Bol et al. and assigned to the assignee of this application.

In the construction of the conductor-seal body, the button of glass is usually first sealed to the metal rod and the rod is then inserted into a

2 tube of vitreous material whose diameter is only slightly greater than that of the rod over most of the length of the tube but is expanded at the end near the button to fit the outer rim of the button, to which it is then sealed. The narrower part of the length of the vitreous tube is then collapsed onto the rod by heating while maintaining a vacuum within the tube. In the case of a tungsten rod and quartz tube, the rod is usually wrapped with a thin metal foil sheet, for example, molybdenum, to prevent the quartz from sticking to the tungsten.

At one end the tube may be formed into or left as a flange for sealing to the sides of a hole in a vitreous envelope as aforementioned. At the other end of the tube there is inevitably left between the rod, the button and the vitreous material a space of appreciable volume, owing to the fact that the collapsing of the vitreous material onto the rod must be limited at this end to preserve the shape of the glass button.

As far as we are aware, such conductor-seal bodies have not been used in the manufacture of high pressure metal vapor electric discharge devices and they are not, in fact, immediately suitable for such use. For if such a conductor-seal body were used in the manufacture of a high pressure metal vapor electric discharge device, such as a lamp to introduce a conductor through the vitreous envelope of the lamp, the length of the conductor-seal body would have to be such that in operation of the lamp the end of the metal rod emerging from the glass button was so far from the envelope that it was, or could be kept, sufficiently cool to prevent the glass button seal being damaged by heat, and also to prevent any appreciable oxidation of the rod. The part of the body near this end of the rod would therefore also be relatively cool in operation and then the metal vapor creeping between the vitreous tube and the metal rod would condense in the said space at the cool end of the tube. Such condensation would lead to lowering of the metal vapor pressure within the lamp, and eventually to a reduction in light output from the lamp.

The object of this invention is to provide conductor-seal bodies of the type specified in the form of stems which can be used on the envelopes of high pressure metal vapor electric discharge devices. Other objects and advantages of the invention will appear from the following description of species thereof.

According to the invention the said space between the metal rod, the glass button and the

adjacent end of the tube of vitreous material is substantially filled with an inert refractory material in powdered form.

The term "inert" implies that the presence of the material must not be injurious to the operation of the device, i. e., must not evolve on heating in operation of the device a gas or vapor which adversely affects the operation of the device, must not react with the metal vapor to produce such a gas or vapor, and must not react with the metal of the rod, the tube of vitreous material or the glass button seal in a detrimental manner.

In a conductor-seal body according to the invention, which is to be used in the manufacture of a high pressure mercury vapor lamp, powdered silica is the refractory material which we prefer to use. Silica is also suitable for use with other metal vapors such as cadmium or zinc. But other suitable powdered inert refractories such as alumina or zirconia may also be used in accordance with this invention.

The powdered material may be introduced into the expanded end of the vitreous tube just before the sealing of the tube to the outer rim of the button and before the collapsing of the tube onto the rod. The powder is preferably packed tightly into the end of the tube. The tube is then sealed to the outer rim of the button and collapsed onto the rod as before. It can be collapsed so closely onto the powder that little or no space is left at the end of the tube which is not filled with powder.

The presence of the powder reduces considerably the volume of metal which can condense in the said space. But since the powder, however tightly packed, must be porous to some extent and permit the condensation of some metal, it is desirable to keep the volume of the said space as small as possible. This is preferably achieved by making the expanded end of the vitreous tube re-entrant and sealing the button to the end of the tube at the bottom of the well formed by the re-entrant end.

In the accompanying drawing, a preferred form of conductor-seal body in accordance with the invention, in which the volume of the said space is kept small in this way, is illustrated by way of example in Fig. 1 which shows the body in the form of a stem in an elevational, partly sectional view; Fig. 2 is a similar view of another species of the invention.

In the embodiment of Fig. 1 the glass button sealed to the metal rod conductor 1 consists of a sleeve 2 sealed to the rod and a dished flange 3 extending from the sleeve. The flange 3 is sealed to, so as to close, the re-entrant end 4 of the expanded end 6 of the tube 5 of hard vitreous material, along the axis of which tube the rod 1 passes, the tube being a close fit around the rod. The open end of the tube 5 is formed as a flange for sealing to the sides of a hole in the envelope of a discharge lamp. In accordance with the invention, the space at the end of the tube 5 between the tube, including the expanded end 6 and re-entrant part 4, the button 2, 3, and the adjacent part of the rod 1, is substantially filled with powdered inert refractory material 7.

A preferred method of making a conductor-seal body of the form shown in Fig. 1 will now be described in detail, and it will be assumed for the purposes of description that the rod is of tungsten, the hard vitreous material is quartz, the button is of intermediate glass, and the refractory material used is silica powder.

In the initial stages of the construction a tungsten rod conductor 1 has sealed around it an intermediate glass button having a dished flange 3 extending from a short sleeve 2 sealed to the tungsten. To the periphery of the flange 3 is sealed a short length of quartz tube 4 so as to form coaxially with the rod 1 the walls of a cup of which the button forms the base. This cup is dimensioned to fit, base first, into the expanded end 6 of a quartz tube 5 whose other end is formed as a flange suitable for sealing into a hole in the envelope of a discharge device, and which is arranged to be a close but sliding fit around the foil-wrapped rod conductor 1 for most of the intermediate part of its length. The thin molybdenum sheet foil wrapping around the rod 1 is shown at 8 in the drawing.

After inserting the foil-wrapped rod 1 into the tube 5 and the cup (2, 3, 4) into the expanded end 6 of the tube 5, held vertically with this end uppermost, finely powdered silica 7 is introduced into the space between the cup and the tube 5 and the tube is tapped to ensure settling and close packing of the powder. Sufficient powder is introduced to fill all the space between the cup, the adjacent part of the rod 1, and the tube (5, 6). The lengths of the tube 4 and expanded part 6 of the tube 5 are arranged so that their ends are adjacent and these ends are sealed together by heating while nitrogen is blown around the outer part of the rod 1 and within the cup, to avoid oxidation of the tungsten. The tube 5 is then collapsed onto the foil-wrapped rod conductor along at least part of its length and is also collapsed, as far as possible, into the powder 7 to reduce the possibility of there being any space left between the sealing button and the quartz tube that is not filled with silica powder. A vacuum is maintained within the tube 5 during the collapsing.

The clearance between the walls of the cup 2, 3, 4 and the expanded end 6 of the tube 5 should be made as small as practicable, consistent with ensuring the safety of the intermediate glass seal during the collapsing of the quartz tube 5 onto the rod 1 and silica powder 7, in order to keep as small as possible the volume of the silica-filled space at the end of the tube.

An alternative form of conductor-seal body in accordance with the invention, which may sometimes be used, is represented in Fig. 2 of the accompanying drawing, which shows the completed conductor-seal body. Corresponding parts of Figs. 1 and 2 are referred to by the same numerals in the two figures.

In this embodiment the sleeve 2 of the glass button is sealed around a metal rod conductor 1, and the rim of the dished flange 3 of the button, extending from the sleeve, is sealed to one end of the quartz tube 4 to form a cup, the rim of which is sealed to the expanded end 6 of the tube 5 of vitreous material with the concave face of the button towards the main part of the seal-body; the rod conductor 1 passes through the tube 5 which is a close fit around the rod. The open end of the tube 5 is formed as a flange for sealing to the sides of a hole in the envelope of a discharge lamp. In accordance with the invention, the space at the end of the tube 5 between the expanded end of the tube 6, the button 2, 3 and the rod 1 is substantially filled with inert powdered refractory material.

A preferred method of making a conductor-seal body of the form shown in Fig. 2 will now be described and it will again be assumed for the

purposes of description, that the rod is of tungsten, the hard vitreous material is quartz, the button is of intermediate glass, and the refractory material is silica powder.

The initial stages of the construction are as described for the previous embodiment, but the cup formed by the button 2, 3 and the short length of quartz tube 4 is in this case dimensioned so that the rim of the cup is adapted to abut against the expanded end part 6 of the quartz tube 5, say along line A—B of Fig. 2, which part 6 is shorter than in Fig. 1. The cup is packed with finely powdered silica 7 and the foil-wrapped rod 1 is then inserted into the tube 5 bringing the cup, rim foremost, into proximity with the expanded end 6 of the tube 5. More silica powder is then introduced through the gap between the rim of the cup and the end 6, into the space formed between the quartz tubes 6 and 4 and the powder is tightly packed by bringing the rim of the cup into abutment with the end of the expanded part of the tube to which it is then sealed by heating while nitrogen is blown around the rod 1 outside the tube 5. Finally, the tube 5 is collapsed onto the foil-wrapped rod conductor and the silica powder as in the previous embodiment.

What we claim as new and desire to secure by Letters Patent of the United States is:

An elongated stem for a high pressure metal vapor electric discharge device having a quartz envelope, comprising a tungsten rod, a quartz tube closely surrounding said rod to provide mechanical support therefor, having one end adapted for fusion with the envelope of the device

and being of enlarged diameter at its opposite end with a re-entrant portion at said end, and intermediate glass body hermetically uniting and constituting the sole hermetic seal between said rod and said tube and being positioned at the inner end of said re-entrant portion to close the enlarged end of said tube, and finely divided refractory inert material filling and tightly packed into the space defined by the rod, the enlarged end of the tube and the glass body to minimize condensation of metal vapor in said stem.
